IMPROVED APPLE PARER.

HORATIO KEYES, OF TERRE HAUTE, INDIANA.

Letters Patent No. 59,843, dated November 20, 1866.

SPECIFICATION.

TO ALL WHOM IT MAY CONCERN:

Be it known that I, HORATIO KEYES, of Terre Haute, in the county of Vigo, and State of Indiana, have invented a new and improved Apple-Paring Machine, and I do hereby declare that the following is a full, clear, and exact description thereof, which will enable others skilled in the art to make and use the same, reference being had to the accompanying drawings forming part of this specification, in which—

Figure 1 is a side view of the machine attached to a table for operating.

Figure 2 is a front view of the same.

Figure 3 is a plan.

Figures 4 and 5 are inverted plans in different positions of the mechanism.

Similar letters of reference indicate like parts.

This invention relates to improvements in the mechanism of apple-paring machines, whereby they are made double-acting and capable of paring apples much faster than ordinary single-acting machines. The operation is such that the paring knife having passed from the back to the front of the apple holder, and thus pared one apple, is thrown down out of the way so that the pared apple can be removed and another put on the fork in its place, to be pared on the return movement of the knife to its first position. In this manner the machine pares continuously and no time is lost in the reverse movement of the paring knife, as in ordinary machines. A is the supporting frame of the machine fastened in the usual way to a table by the thumb-screw *a*; B is the driving wheel turned by the crank *b*; C is the holding fork rotated by the pinion *D*, which gears into the driving wheel *B*. On the inner end of the short shaft of the driving wheel *B*, is placed a small bevel wheel *c* which engages in a larger horizontal bevel wheel *c'*, upon the upper side of which is affixed concentrically a segmental spur wheel *d*, which engages in another segmental wheel *d'*, supported by the axis *e*, on a projection *A'* shown in figs. 2 and 4. On the segmental wheel *d'* is mounted the paring knife *f*, affixed to the arm *f'* which works at the lower end on the axis *g*, around which is wound a spiral spring, *g'*. On the bottom of the knife arm *f'* are several cogs which engage in corresponding cogs on the segmental edge of a small lever brake *h*, which lies under the axis *g*, and is pivoted by the axis *e*. On the end of the axis *e*, opposite the segmental wheel *d'*, is affixed another segmental spur wheel *i*, figs. 4 and 5, which gears into a curved rack *j*, on the inner side of the rim of an eccentric rack frame *k*, which centres and moves on a pivot *l*, set in the frame *A* near the bevel wheel *c*, as shown in fig. 3. On the under side of the bevel wheel *c'*, a pin, *m*, projects opposite the last cog on one side of the segmental set of cogs upon it, which pin *m* catches against the projecting arm *n*, on the inner side of the rack frame *k*, for moving it forward as the bevel wheel *c'* rotates, giving a return movement of half a revolution to the paring knife *e*, which is the peculiar and essential feature of this invention. It will be observed when the machine is operated that the bevel wheel *c'* is moved forward as indicated by the arrows in figs. 4 and 5, that the last cogs in the segment *d*, are engaged in the last cogs in segment *d'*, after having made half a revolution of the bevel wheel *c'*, which half revolution has carried the paring knife *e*, from the bottom to the top of the holding fork *C*, and thus pared one apple. At this point of the operation of the machine the lever brake *h*, comes into play by bearing its extremity against the periphery of the bevel wheel *c'*, the effect of which is to turn the lever brake a little on its pivot *e*, and by means of the cogs in its segments edge working in the cogs on the bottom of the knife arm *f'*, throw the arm and paring knife down flat out of the way the moment the apple has been pared by the first half revolution of the bevel wheel *c'*. Just as the cog on the segments *d d'*, have passed each other so that the segment *d'*, is released from the segment *d*, the pin *n* on the lower side of the bevel wheel opposite the last cog on the segmental wheel *d*, takes up the movement by catching into the crotch of the projection *n*, on the inner side of the eccentric rack frame *k*, and while the bevel wheel *c'* continues to revolve in the same direction as before, the pin *m* bears against the projection *n*, and thus pushes the rack frame *k* forward, when the cogs in the rack *j* engage in the cogs in the segment *i*, figs. 4 and 5, and give it half a revolution, thus reversing the movement of the wheel *i* in the rack *j*, and also of the paring knife, which then resumes its upright position and is carried back to its starting point by the remaining half revolution of the bevel wheel *c'*. It will be observed that as the bevel wheel *c'* revolves and carries forward the rack frame *k*, which also turns on the pivot *l*, the movements are on different centres as indicated red, figs. 4 and 5, and that the pin *m* rises on the projection *n*, and passes over at the moment the segment wheel *i* has travelled over the rack *j*, when the operation on the paring knife is then again taken up by the segmental wheels *d d'*, as first described, and the wheel *i* returns to the other end of the rack *j*, to resume

reverse action at the end of the next half revolution of the bevel wheel c' , and thus continue the double acting operation of the machine.

Having thus fully described the construction and operation of my improvements, what I claim as new, and desire to secure by Letters Patent, is—

1. I claim the segmental wheels $d d'$, in combination with the lever brake h , and the paring-knife arm f' , constructed and arranged substantially as and for the purposes herein described.

2. I claim also the segmental wheel i , and the pin m , in combination with the eccentric rack frame k , and rack j , constructed and arranged substantially as and for the purposes herein specified.

3. I claim also the combination and arrangement of the bevel wheel c' , with the segmental wheels $d d'$, the pin m , the segmental wheel i , the eccentric rack frames k , the lever brake h , and the knife arm f' , constructed and operated substantially as and for the purposes herein set forth.

HORATIO KEYES.
